UNITED STATES PATENT OFFICE.

EMMET P. GRAY, OF DETROIT, MICHIGAN.

MUFFLER.

1,276,209.

Specification of Letters Patent. Patented Aug. 20, 1918.

Application filed March 30, 1918. Serial No. 225,635.

To all whom it may concern:

Be it known that I, EMMET P. GRAY, a citizen of the United States, and residing at Detroit, in the county of Wayne and State 5 of Michigan, have invented a new and Improved Muffler, of which the following is a specification.

This invention relates to means for reducing the sound of the exhaust of internal 10 combustion engines and its object is to provide a device of this character which shall produce a minimum amount of back pressure while at the same time have maximum efficiency as a muffler.

15 This improved muffler for internal combustion engines consists in a series of cylinders, one within the other connecting by means of a number of holes through their walls, of heads closing the ends of the cylinders, the inlet head being provided with a passage to conduct the exhaust of the engine to the interior of the inner cylinder and the other head having a series of passages connecting a conduit with the spaces between 20 the cylinders and within the inner cylinder. It also consists in forming the discharge passages in the outlet head of increasing areas from the central cylinder outwardly and with their total areas less than the area 25 of the intake opening of the muffler. It also consists in providing a safety valve in the intake head to relieve the muffler of excessive pressures.

In the accompanying drawing, Figure 1 30 is a central longitudinal section of this improved muffler. Fig. 2 is a partial elevation of the inlet end thereof. Fig. 3 is an outer elevation and Fig. 4 an inner elevation of a modified form of outlet head for this muffler. 35 Fig. 5 is a section on the line 5—5 of Fig. 3. Fig. 6 is a view of the outlet head shown in Fig. 1, one half being in elevation and one half in section on the line 6—6 of Fig. 1.

Similar reference characters refer to like 40 parts throughout the several views.

The pipe 1 connects this muffler to the engine and through this pipe the exhaust gases of the engine is conducted into the inlet head 2. A deflecting plate 3 guides the gases 45 toward the opening 4 which is surrounded by the annular ribs 5, 6 and 7 that position the muffling cylinders 8, 9 and 10. A cross bar 12 supports a bolt 13 which guides a safety valve 14, normally held down on its seat 15 by the spring 16. Should excessive

pressures occur within the head 2, this valve will rise and permit the gases to escape.

At the opposite end of the muffler is an outlet head 17 having ribs 18, 19 and 20 to position the cylinders 8, 9 and 10. Bolts 60 22 may screw into proper holes in the head 2 and receive nuts 23 and thus hold the parts in position. The cylinder 8 is provided with a series of holes 24 to permit the exhaust gases to pass to the space between it and the 65 cylinder 9. The exhaust then passes around this cylinder 9 to the holes 25 and to the space between it and the outer cylinder 10. The number and size of these holes will depend upon the engine, but the combined area 70 of the holes in either cylinder 5 or 6 is preferably slightly less than the area of the pipe 1.

The head 17 is formed with a chamber 30 and with passages 27, 28 and 29 for the 75 exhaust gases. The wall of this chamber 30 is bent inward at 32 around the bolts 22 to permit the nuts 23 to be turned. A stud-bolt 34 extends in alinement with the discharge opening 33 in the head 17 and carries the 80 rotatable second chamber 35, lugs 36 on the latter centering it on the head 17. A discharge pipe 37 is mounted to connect to this chamber 35 which may be locked in any desired position by the nut 38. The two heads 85 may have feet 39 and 40, if desired.

The exhaust gases rush into the inner cylinder 8 and the major portion passes out through the holes 24 into the cylinder 9, and fills that cylinder, passing then through the 90 holes 25 into the cylinder 10 and out through the passages 29. I have found that the pressure within the cylinder 8 and therefore the back pressure in the exhaust pipe 1 is greatly reduced by forming the passage 27 in the 95 head 17. The action seems to be in the nature of an ejector, the jet of gas from this passage 27 driving the gases in the chamber 30 out before it and serving by its friction with the gases coming from the passages 28 100 and 29 to draw these gases from the cylinders 9 and 10, these gases in turn serving to reduce the speed of the gas coming from the passage 27. This so reduces the speed of the gas from the passage 27 that the cylinder 8 105 does not become empty after one explosion before it is filled from the next. The discharge from the passages 27, 28 and 29 is therefore substantially continuous. This direct flow of the gases from these passages 110

serves to blow out from the cylinders all carbon, grease and other matter that may collect therein. This action is intensified by the action of the jet from the passage 28, 5 but the individual result obtained is not as great as that from the passage 27. The flow of exhaust gases through these passages 27 and 28 is almost noiseless and cannot be detected a few feet away. The outer chamber 10 35 may be turned to cause the pipe 37 to extend at any desired angle.

In Figs. 3 to 5 inclusive, an outlet head 44 is shown provided with annular ribs 45, 46 and 47 to receive the ends of the cylinders 8, 15 9 and 10 and with holes 48 to receive the ends of the bolts 22. The head has passages 49, 50 and 51 that connect into the interiors of the cylinders 8, 9 and 10 respectively, and into the interior of the spout 53, as shown in 20 Fig. 5. It will be noticed that the passage 51 is very much larger than the other two combined.

The dimensions and proportions of the various details may all be varied without 25 departing from the spirit of this invention set forth in the following claims.

I claim:—

1. In a muffler the combination of a series 30 of concentric cylinders, the interior cylinder having passages to permit the outward flow of exhaust gases, an inlet head at one end of the cylinders having a passage to conduct gases to the interior of the inner cylinder, an outlet head and a chamber on the outer side 35 thereof, said outlet head being formed with a series of passages connecting said chamber to the chambers formed between the walls of the cylinders.

2. In a muffler, the combination of a series 40 of concentric cylinders, the interior cylinder having passages to permit the outward flow of exhaust gases, an inlet head at one end of the cylinders having an inlet passage at right angles to the line of said cylinders to 45 admit exhaust gases and an interior passage in alignment with the interior cylinder to conduct the gases thereto, an outlet head and a chamber on the outer side thereof, said outlet head being formed with a series of 50 passages connecting said chamber to the chambers formed between the walls of the cylinders.

3. In a muffler, the combination of a series

of concentric cylinders, the interior cylinder having passages to permit the outward flow 55 of exhaust gases, an inlet head at one end of the cylinder having an inlet passage at right angles to the line of said cylinders to admit exhaust gases and an interior passage in alignment with the inner cylinder to conduct 60 the gases thereto, said head being formed with a curved deflector to cause the gases to flow freely into said inner cylinder, an outlet head closing the opposite ends of said cylinders and a chamber on the outer side 65 thereof, said outlet head being formed with a series of passages connecting said chamber to the chambers formed between the walls of the cylinders.

4. In a muffler, the combination of a series 70 of concentric cylinders, the interior cylinder having passages to permit the outward flow of exhaust gases, an inlet head at one end of the cylinder having an inlet passage at right angles to the line of said cylinders to 75 admit exhaust gases and an interior passage in alignment with the inner cylinder to conduct the gases thereto, said head being formed with a curved deflector to cause the gases to flow freely into said inner cylinder, 80 and with an opening in alignment with the inlet passage, a safety valve normally closing said opening and a spring to hold the valve onto its seat, an outlet head and a chamber on the outer side thereof, said outlet head being formed with a series of 85 passages connecting said chamber to the chambers formed between the walls of the cylinders.

5. In a muffler, the combination with a series 90 of concentric cylinders, the interior cylinder having passages to permit the outward flow of exhaust gases, an inlet head at one end of the cylinders having a passage to conduct gases to the interior of the inner cylinder, an outlet head and a rotatable chamber on the outer side thereof, said outlet head being formed with a series of 95 passages connecting said chamber to the chambers formed between the walls of said cylinders, and means to hold said chamber in any desired position, the innermost passage in the outlet head being of less area than any 100 of the others.

EMMET P. GRAY.
